UNITED STATES PATENT OFFICE.

ARTHUR G. LEBEL, OF BIDDEFORD, MAINE.

ELEVATOR ATTACHMENT.

1,303,685.

Specification of Letters Patent.

Patented May 13, 1919.

Application filed January 29, 1919. Serial No. 273,766.

To all whom it may concern:

Be it known that I, ARTHUR G. LEBEL, citizen of the United States, residing at Biddeford, in the county of York and State 5 of Maine, have invented certain new and useful Improvements in Elevator Attachments, of which the following is a specification.

This invention relates in general to elevators and specifically to a safety attachment 10 for the elevator and a standing platform or floor thereadjacent.

One object of this invention is the production of an elevator attachment wherein corresponding supporting structures are 15 provided at the edge of the elevator flooring and also at the edge of the flooring of a supporting structure adjacent the elevator shaft, whereby when the elevator descends or ascends and a person's foot may be accidentally protruding in the path of movement of the elevator or near the floor of the supporting structure, the attachment will swing to release the foot without injury thereto.

25 Another object of this invention is the production of an attachment for an elevator which is in the nature of a safety device for preventing a person's foot from being caught and injured or the person being held in position where he will be injured in the event the elevator starts while the foot is protruding where the movement of the elevator will effect the same.

30 One practical form of construction and assembly of the present invention will be hereinafter described and is illustrated in the drawing, in which—

Figure 1 is a top plan view of the elevator attachment showing how the devices on the 40 floor of the elevator and the floor of the supporting structure coöperate with each other.

Fig. 2 is a section taken on the line 2—2 of Fig. 1.

Fig. 3 is an enlarged fragmentary sectional view of a portion of the device taken 45 on the line 3—3 of Fig. 1, and

Fig. 4 is a vertical section taken on the line 4—4 of Fig. 3.

In the preferred embodiment of the present invention about to be described, 5 indicates the floor of an elevator car and 6 the floor of a building or any other fixed support.

The floor of the car and the floor 6 of the 55 supporting structure are cut away to form elongated recesses 7, as shown in Fig. 1,

thereby causing the inner edges of the floor 5 and the floor 6 to be spaced apart as shown in Fig. 2.

It might be stated that the construction 60 of the safety device on the floor of the elevator car is identical with the construction of the safety device on the floor 6 of the supporting structure, and for this reason the description of the construction of one device 65 will clearly illustrate the construction of the other device. Each floor is provided with a reinforcing strip 8 adjacent the inner surface of the recess 7, thus preventing the floor from wearing or breaking off where the 70 point of strain bears thereon.

The floors are provided with parallel grooves 9 formed in their upper surfaces, the grooves extending inwardly from the inner edges of the recesses 7. Supporting 75 bars 10 removably fit within the recesses and for this reason extend substantially flush with the upper surface of the floors, as shown in Fig. 2. Each bar 10 has a reduced portion 11 at its inner end and a pocket 12 is 80 formed in the upper portion of the reduced portion 11. Bolts 13 extend through the floors and have eyes 14 at their upper ends fitting in the grooves 9 of the floors and extending transversely to the grooves. These 85 eyes fit within the pockets 12, as shown clearly in Figs. 3 and 4, and are held against displacement by the nuts 15 mounted on their lower projecting ends. By providing the reduced portions at the inner ends of the 90 bars, sufficient space is provided for the accommodation of the eyes 14 of the bolts, as is obvious from an inspection of Fig. 1. With this construction it will be seen that the supporting bars 10 are pivotally mounted upon 95 the floors and normally fit within the grooves.

A comparatively broad elongated supporting plate 16, which is only slightly smaller than the recess of each flooring is connected 100 by the elements 17 upon the bars of each flooring. Thus a plurality of such plates are employed and extend parallel and very near to each other. Since these plates are fixed upon their respective supporting bars 105 10, each series of bars and its respective supporting plate 16 constitutes the protector grating for purposes to be hereinafter set forth. It should be noted that the bars 10 normally fit upon the supporting strips 8 110 which are countersunk below the level of the inner surfaces of the grooves 9.

Very often, a person's foot may be projecting either beyond the edge of the elevator car floor or beyond the edge of a supporting floor and when the elevator starts the person's foot is caught and jammed between the elevator and the supporting structure which not only often results in serious injury to the foot or limb of such person but often throws the body of the person into position where he is seriously injured and sometimes fatally injured. In connection with the present device however if the elevator car is slightly below the level of the floor 6 of the supporting structure and a person's foot projects beyond the supporting plate 16 of the elevator car floor 5, obviously, downward movement of the elevator car will not cause the person's foot to be caught, although upward movement under ordinary conditions would cause such action. In connection with the present invention however, the person's foot would strike the surface of the supporting plate 16 of the floor 6 and upon continued upward movement of the elevator car, the protector grating of the floor 6 would swing upwardly by the pivoting of the inner end of the bars 10 upon their respective bolts. As soon as the person's foot is disengaged, the protector grating would fall back down to its normal position. The same action would result if the person was standing upon the plate 16 of the floor 6 with his foot projecting beyond the plate. Downward movement of the elevator car suddenly would cause the plate 16 of the floor 5 of the elevator car to be swung upwardly by the swinging of the bars 10, thus allowing the elevator car to pass on down without injury to the person's foot or limb or body as above explained, as soon as the person's foot is disengaged, the protector plate of the elevator car floor would fall back down to its normal position.

Under normal conditions, the protector grating extends flush with the floors and a person may walk thereover without stumbling or without interference from these gratings.

The foregoing description and drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:—

60 1. In a device of the class described, the combination of an elevator car and a supporting structure, said car and structure having counter-sunk grooves formed therein, supporting bars pivotally mounted within said grooves, supporting plates fixed upon

said bars, whereby said plates and bars normally fit flush with the surface of the elevator car and the supporting structure, although one or the other plates may swing when an article is in the path of movement thereof.

2. In a device of the class described, the combination of an elevator car and a supporting structure, said car and structure having counter-sunk grooves therein, bars fitting within said grooves, said bars having reduced portions provided with sockets therein, bolts carried by said car and structure and having eyes carried within said grooves and fitting within said sockets, thus pivotally supporting said bars, and supporting plates fixed upon the opposite ends of said bars, whereby if one or the other plate engages a protruding article, the plate and bars so engaged will be swung upwardly to disengage such an article without injury thereto.

3. In a device of the class described, the combination of a supporting structure and an elevator car having contiguous edges cut away to form elongated recesses, grooves formed in said car and supporting structure and extending inwardly from said recesses, bars pivotally mounted within said grooves, reinforcing strips carried adjacent the outer ends of said grooves, said bars resting upon said strips, supporting plates fixed upon the outer ends of said bars in alinement with said recesses, thus forming protector gratings, whereby when one grating is engaged by a protruding article, it will swing to disengage the article without injury thereto.

4. In a device of the class described, the combination of a supporting structure, and an elevator car having contiguous edges cut away to form elongated recesses, grooves formed in said car and supporting structure and extending inwardly from said recesses, bars pivotally mounted within said grooves, supporting plates fixed upon the outer surface of said bars in alinement with said recesses, thus forming protector gratings, whereby when a grating is engaged by a protruding article it will disengage the article without injury thereto.

5. In a device of the class described, the combination of a supporting structure, and an elevator car, grooves formed in said car and supporting structure, bars pivotally mounted within said grooves, supporting plates fixed upon the outer ends of said bars, thus forming movable protector gratings.

6. In a device of the class described, the combination of a supporting structure and an elevator car, grooves formed in said car and supporting structure, bars positioned within said grooves, eye bolts carried within said grooves and engaging the inner end of said bars for pivotally supporting the

bars remote from the forward edges of the supporting structure and car, and supporting plates fixed upon the outer end of said bars thus forming movable protector grat-
5 ings.

7. In a device of the class described, the combination of a supporting structure and elevator car, grooves formed in said car and supporting structure, bars positioned within 10 in said grooves and having pockets in their inner ends, bolts having eyes positioned within said grooves and being received within said pockets, thus pivotally receiving the bars in the grooves although the bolts will 15 be below the level of the car and supporting structure, and supporting plates fixed upon the outer end of said bars, thus forming movable protector gratings.

8. In a device of the class described, the combination of a supporting structure and 20 elevator car, protector gratings pivotally mounted upon said car and said supporting structure at a distance from the outer edges of said car and structure although projecting beyond the outer edges, said grat- 25 ings being countersunk below the supporting level of said car and supporting structure to prevent tripping thereover although said grating may be easily moved when necessary.

In testimony whereof I affix my signature in presence of two witnesses.

ARTHUR G. LEBEL.
